UNITED STATES PATENT OFFICE.

CHARLES STETLER, OF CLARK SUMMIT, PENNSYLVANIA.

MAIL-BAG-CATCHING DEVICE.

Application filed August 17, 1925. Serial No. 50,753.

The object of this invention is to provide improved means for supporting a mail bag above a track, in such manner that the bag will be released upon engagement by a lever operated member adapted to be swung upwardly from the roof of a mail car, as the latter approaches a station.

A further object is to provide a supporting device comprising a vertical element and a cross bar rotatably connected with the lower end thereof, this bar having pivotally connected with its ends two depending arms which detachably support a horizontal strip holding the mail sack, and from which it is released by contact of the aforesaid lever operated member carried by the car.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 shows an arch-like structure to be erected over the track at the point where the mail is to be picked up by moving trains, this view also showing the car carried catching device, all in elevation;

Figure 2 is a top plan view of the same structure;

Figure 3 is a vertical section, on line 3—3 of Figure 2;

Figure 4 is a vertical section on line 4—4 of Figure 2;

Figure 5 is a view in vertical section and elevation, showing the bag supporting means mounted on the upper portion of the arch of Figure 1;

Figure 6 is a view in section and elevation, showing the bag supporting means per se, and in the position assumed when the bag is being released;

Figure 7 shows the structure of Figure 6, when looking from the right in that view;

Figure 8 shows the lower apertured bar of Figures 5 and 6, designed to receive a ring member by means of which the bag is suspended with a short rope.

In Figure 1 the track structure including the rails is designated 10, and a car body is shown conventionally and is designated 11. Columns 12 and 13, on opposite sides of the track, support upper parallel girders or bars 14 and 15, Figures 1 and 2, thus completing

the structure, which for convenience may be termed an arch.

On the upper portion of the arch a vertical tubular member 16 is mounted, this element being covered by a guard 17 providing a small housing 18 for pulley wheel 18' for guiding rope 19 which passes to one of the side columns and over pulley 20, and thence downwardly to a securing device 21. Within tube 16 is a bar 23, connected with the cord or rope 19, the bar being accurately guided within the tube, so that the bag will retain proper position centrally of the track.

A cross bar 24 is swiveled or rotatably connected on the lower end of bar 23 and includes ears 24' for mounting depending pivoted bars 25, 26, each apertured at 27 for supporting the ends of lower cross bar 28. The latter suspends the mail sack by means of cord 30 and ring member or loop 31. The bag may swing about the pivotal point 23', but the car carried device referred to below, will bring it to the position of Figure 6, owing to contact of ring member 31 with depending bar 25 or 26 of the frame.

Since bar 28 must be kept from falling, I provide cords or chains 34, 35, secured at 36, and having their lower portions passing through apertures 27, and thence to pins 37 entering apertures or slots 38 in bar 28. After the bag takes the position of Figure 6, strain on chain 34 releases one pin 37, but bar 28 is held by the other chain. Vertical bar 23 may then be drawn upwardly by rope 19. In Figure 6 the left end of the bar 28 having been released, all of the strain is on the left pin 37, and this tends to free itself and release the bag, and as there is no further strain on the bar 28 the latter would usually be retained by frictional engagement with the walls of the aperture 27 at the right. However the temporary loss of the bar 28 under unusual circumstances is not of great importance, as it costs little, and may often be recovered, but the replacing of the bar is a simple matter, assuming that extra bars are on hand.

The car carried device includes rack 40, shown especially in Figures 3 and 4, and comprising a frame formed of curved bars suitably connected, and carried by rotatable rod 42 mounted in bearing brackets 43' within the car and below the roof thereof. The roof 43 has an opening 44 closed by a trap door 45 hinged or pivoted at 46,

and the door is lifted when hand lever 47 swings the frame or rack 40 for throwing it to operative position. In this position the sack is directly caught, as indicated in Figure 1, and drops into the car at once, or as the result of the operation of lever 47.

A mail car using this device will be equipped with two swinging frames, to permit of operation in both directions, and the apparatus is especially designed to permit of use for picking up mail by airplanes in flight, it being understood that much greater space within the arch would be provided.

What is claimed is—

- 15 1. A mail bag supporting device, comprising a track bridging structure, a vertical tubular element carried thereby, a rod telescoping with the tubular element, a cross bar swiveled to the rod, depending arms pivoted to the cross bar, in spaced relation, and a detachable bar passing loosely through end portions of the depending arms.
- 20 2. A mail bag supporting device, comprising a vertical element, a cross bar having rotatable connection therewith, depending arms pivoted to the cross bar, a detachable bar loosely connected with the depending arms, and flexible devices independent of the arms and of greater length,

these devices being connected with the cross bar and removably connected with the detachable bar and separable therefrom under strain.

3. A mail bag supporting device, comprising a vertical element, a cross bar swiveled thereto, depending arms pivoted to the ends of the cross bar, and movable outwardly from a vertical position, the lower ends of the arms being apertured, a lower bar having its ends entering the apertures, and a ring member through which the lower bar passes, the ring member being adapted to support a bag.

4. A mail bag supporting device, comprising a vertical element, a cross bar pivoted thereto, depending arms pivoted to the ends of the cross bar and movable outwardly from a vertical position, the lower ends of the arms being apertured, a lower bar having its ends entering the apertures, a ring member through which the lower bar passes, the ring member being adapted to support a sack, and flexible devices connected with the cross bar and with said lower bar.

In testimony whereof I affix my signature.

CHARLES STETLER.
